(57) **CLAIM**

The ornamental design for a gateway set-top box enclosure, as shown and described.

DESCRIPTION

FIG. 1 is a perspective view of a front side, top side, and right side of a gateway set-top box enclosure.

FIG. 2 is a front elevation view of the gateway set-top box enclosure.

FIG. 3 is a right side elevation view of the gateway set-top box enclosure. The left side elevation view of the gateway set-top box enclosure is a mirror image of the right side elevation view of the gateway set-top box enclosure; and,

FIG. 4 is a rear elevation view of the gateway set-top box enclosure.

The broken lines immediately adjacent the claimed areas represent the bounds of the claimed design while all other broken lines are directed to environment and are for illustrative purposes only; the broken lines form no part of the claimed design.
